[57] CLAIM

The ornamental design for a appliance safety latch, as
shown and described.

DESCRIPTION

FIG. 1 is a top, front, and left side perspective view of
an appliance safety latch showing my new design, the
broken-line disclosure of a refrigerator being for illustra-
tive purposes only and forming no part of the
claimed design;

FIG. 2 is an enlarged top, front, and right side perspec-
tive view thereof;

FIG. 3 is an enlarged right side elevational view
thereof;

FIG. 4 is an enlarged left side elevational view thereof;

FIG. 5 is an enlarged bottom plan view thereof; and,

FIG. 6 is an enlarged rear elevational view thereof.
